SPRAY MAST MOUNTING

Ralph D. Malin, East Lansing, Mich., assignor to
Food Machinery and Chemical Corporation, a
corporation of Delaware

Application October 1, 1947, Serial No. 777,340

7 Claims.

(Cl. 299—72)

1. A spray rig for use with a farm tractor

This invention relates to spray rigs employed for spraying orchards with insecticides and more particularly to spray masts carried by said rigs.

A spray mast of the character mentioned usually carries a series of nozzles spaced vertically from each other along the mast. These nozzles are supplied with liquid through the mast itself and it is desirable to control the direction in which the nozzles point in a horizontal plane by rotation of the mast itself and to provide a control by which the vertical angle of the nozzles may also be governed during the operation of the rig equipped with this mast.

When moving the rig on a highway or when storing the same, it has been found highly desirable to dismount the mast or provide a hinged coupling on the same near its lower end so that the mast may be laid horizontally on the rig just above the top of the tank.

It is an object of this invention to provide a spray mast including a novel and inexpensive means of mounting said mast on a rig which will facilitate operation of the mast in the manner above described and also provide for the mast being readily dismounted for purposes of travel or storage, and remounted on the rig in a short time and by a single person.

It is another object of the invention to provide such a spray mast and mounting therefor in which means is provided for locking the mast in any desired rotational position in said mounting.

The manner of accomplishing the foregoing objects as well as further objects and advantages will be made manifest in the following description taken in connection with the accompanying drawings in which:

Fig. 1 is a rear elevational view of a spray rig with which is incorporated a preferred embodiment of the present invention.

Fig. 2 is an enlarged vertical sectional view taken on the line 2—2 of Fig. 1.

Fig. 3 is a horizontal sectional view taken on the line 3—3 of Fig. 2.

Fig. 4 is a horizontal sectional view taken on the line 4—4 of Fig. 2.

Fig. 5 is a fragmentary sectional view taken on the line 5—5 of Fig. 2 and illustrating the socket clamp of the invention.

Referring specifically to the drawings, the invention is there shown as embodied in a spray rig 10 having a mast socket 11 in which is mounted a spray mast 12.

The rig 10 comprises a frame 13 supported on wheels 14 and adapted to be hitched while in

use to a farm tractor. Supported on the rig frame 13 is a spray solution tank 15 and an operator's platform 16.

The socket 11 has a tubular body 20 which is integrally united with a base plate 21 and three reinforcing webs 22, the plate 21 being rigidly united with the platform 16 in parallel spaced relation therewith by four posts 23. This holds the tubular body 20 of the mast socket 11 in upper right position on the rig 10 as shown in Figs. 1 and 2.

The tubular body 20 of the socket 11 has a slot 24 which extends from the upper end thereof to a point near the lower end of the body. The latter also has an internal shoulder 25 provided therein as shown in Fig. 2, this shoulder being formed by a split ring welded to the inside of the tubular body 20.

Welded to the upper end of the tube 20 on opposite sides of the slot 24 are lugs 29 and 30 of a clamp 31 formed by a screw 32 freely extending through a hole in lug 30 and screwing into threads provided in a similar hole in the lug 29.

By the operation of this clamp, the upper end 25 of the tube 20 may be constricted or relaxed at the will of the operator for a purpose to be made clear hereinafter.

Welded to the exterior of the tube 20 is a bracket 33 supporting a valve 34 which is connected by a hose 35 to the solution supply tank 15.

The spray mast 12 may be any multiple-gun mast suitable for use with a spray rig but is shown herein as comprising a "Stockdale" mast, a detailed disclosure of which is contained in the co-pending application of Harry C. Stockdale, Serial No. 653,990, filed March 13, 1946 on a "Spray Mast," now Patent No. 2,511,021.

The mast 12 differs from that shown in the co-pending application only in its being equipped with a lever 40 for moving nozzles 41 thereof horizontally and vertically to determine the direction in which spray is discharged from these nozzles.

45 The spray mast 12 is also equipped with a handle 42 which the operator, standing on the platform 16, may hold to with one hand while the other hand is used in actuating the lever 40.

The spray mast 12 has a main mast tube 50 a lower portion of which is reinforced by a smaller tube 51 which snugly fits the inner diameter of the tube 50 and is welded therein.

At its lower end the tube 50 is threaded to connect with a liquid transmitting swivel or stuffing box 53 which includes a shell 54, the

upper end of which has an internally threaded bore 55 to receive the tube 50 and has an external shoulder 56 provided thereon. The bore 55 has a counter-bore 57, the mouth of which is threaded.

Extending into the counter-bore 57 is a pipe 59 having an external shoulder 60 which is pressed against the upper end of the counter-bore. Pipe 59 is surrounded by a gland 62 which is screwed into the lower end of the counter-bore 57 to compress packing 63 into this space between the pipe 59 and the counter-bore.

The lower end of the pipe 59 is connected by an elbow 64 to a hose nipple 65 which is connected by a flexible hose 66 to the valve 34.

Snugly receiving the stuffing box 53 and secured thereto just beneath the shoulder 56 by set-screws 70 is a collar 71 which rotatably rests upon the internal shoulder 25.

Surrounding the spray mast tube 50 at the upper end of the tube 20 is a cap 75 which covers the upper end of this tube and extends into the tube so as to cooperate with the collar 71 in holding the spray mast tube 50 in co-axial alignment with the socket tube 20.

Operation

In the drawings, the mast 12 is shown as installed in the socket 11 ready for operation. The collar 71 is shown as resting on the internal shoulder 25 and the cap 75 is shown as resting on the upper end of the tube 20. Both collar and cap are shown as secured to the spray mast 12 so as to rotate therewith when this is turned by manipulation of the lever 40.

In this arrangement, the supporting of the weight of the spray mast 12 might be shared by the cap 75 but it has been found preferable in practice for this cap to be set upon the mast tube 50 so that when the mast is mounted in the socket, the weight is borne entirely by the collar 71.

When it is desired to dismount the mast 12, the screw 32 is unscrewed from the threaded lug 30 and withdrawn from the other lug. The operator then stands on the tank 15 close to the mast 12 and lifts this directly upward out of the socket tube 20. The hose nipple 65 slides upwardly in the slot 24 and the collar 71 and cap 75 readily slide upwardly out of this tube.

The screw 32 is tethered by a suitable chain so that this will not be lost.

While dismounted, the mast is laid horizontally and longitudinally along the top of the spray rig 10 and lashed in place by ropes or, if desired, suitable clamping devices are provided on the tank 15 to secure the mast in place while it is dismounted.

To remount the mast 12, the dismounting operation is merely performed in reverse. The operator first releases the mast from whatever was used to secure it in horizontal position. He then stands on the tank 15, lifts the mast into vertical position, lowers it downward into the socket 20 with the hose nipple 65 guided by the slot 24 and with the collar 71 and cap 75 guided by the internal surface of the socket tube 20.

The screw 32 is now replaced in lugs 29 and 30 to assemble the clamp 31 and the latter is tightened to grip the cap 75 and lock the mast 12 in assembled relation with the socket 11 until operation of the spray mast requiring rotation of the latter in the socket 11 is about to begin.

When the mast 12 is rotated about its own axis through manipulation of the lever 40, the slot 24 engages the hose nipple 65 and prevents rotation

of the pipe 59 with the stuffing box 53 and the mast 12.

I claim:

1. In a spray rig, the combination of: a frame; a tubular socket, the length of which is substantially longer than its diameter, said socket having a slot extending downward from its upper end a substantial portion of its length; a mount on said frame for rigidly supporting said socket in an upright position thereon; a tubular spray mast; a stuffing box provided upon the lower end of said mast; a spray liquid supply pipe, having a right angle turn therein, and swivel-connected coaxially with said mast through said stuffing box, said mast being removably insertable into said socket with said pipe extending out through said slot; a pair of collars spaced a substantial distance apart on said mast and engaging said socket to centralize said mast therein, at least one of said collars engaging said socket to support the weight of said mast on said socket; and means on said frame for supplying spray liquid to said pipe.

2. A combination as in claim 1 in which an internal shoulder is provided in said socket to be engaged by one of said collars for the support of said mast on said socket.

3. A combination as in claim 1 in which an internal shoulder is provided in said socket to be engaged by the lower of said collars for the support of said mast on said socket.

4. A combination as in claim 1 in which said stuffing box has an outer sleeve, the upper end of said sleeve being tapped to threadedly receive the lower end of said mast; an external flange provided on said sleeve, the lower of said collars fitting upwardly over said sleeve and against said flange; and a shoulder extending inwardly from said socket against which shoulder said lower collar rests to support the weight of said mast on said socket.

5. A combination as in claim 1 in which a valve for controlling the supply of spray liquid to said pipe is mounted on said socket above the level halfway between the top of said socket and said pipe; and a flexible hose connecting said valve with said pipe.

6. A combination as in claim 1 in which said collars are both fixed upon said mast and engage said socket to support said mast on the latter; in which said collars are rotatable relative to said socket while thus supporting said mast; and a handle extending laterally from said mast for rotating the same in said socket.

7. A combination as in claim 1 in which the upper of said collars extends downwardly into the upper end of said socket when said mast is supported in the latter; and a clamp for constricting the upper end of said socket to optionally secure said upper collar and said mast against rotation in said socket.
